(57) **CLAIM**

The ornamental design for a video conference machine, as shown and described.

DESCRIPTION

FIG. 1 is a front perspective view of a video conference machine showing my new design;

FIG. 2 is a perspective view of change state 1 thereof;

FIG. 3 is a perspective view of change state 2 thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is an enlarged view of the encircled portion 10 of FIG. 1; and,

FIG. 11 is an enlarged view of the encircled portion 11 of FIG. 1.

The dashed broken lines encircling portions of the claimed design in FIG. 1 that are illustrated in enlarged views in FIGS. 10-11, respectively, form no part of the claimed design. The other broken lines in the drawings illustrate the portions of the video conference machine which form no part of the claimed design.

1 Claim, 11 Drawing Sheets
